UNITED STATES PATENT OFFICE.

ARTHUR R. WILFLEY, OF DENVER, COLORADO.

ACTUATING MECHANISM FOR CONCENTRATORS.

SPECIFICATION forming part of Letters Patent No. 783,342, dated February 21, 1905.

Application filed June 14, 1898. Renewed December 24, 1904. Serial No. 238 227.

To all whom it may concern:

Be it known that I, ARTHUR R. WILFLEY, a citizen of the United States of America, residing at Denver, in the county of Arapahoe and 5 State of Colorado, have invented certain new and useful Improvements in Actuating Mechanism for Concentrators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in actuating mechanism for concentrators; and it consists of the features, arrangements, and combinations hereinafter described and claimed, all of which will be fully understood 20 by reference to the accompanying drawings, in which is illustrated an embodiment thereof.

In the drawings, Figure 1 is a top view of my improved apparatus, the belt being omitted. Fig. 2 is a side elevation of the table, 25 shown partly in section. Fig. 3 is a section taken on the line $z z$, Fig. 1. Fig. 4 is a top or plan view of the operating mechanism, the parts being shown on a larger scale. Fig. 5 is a section taken on the line $x x$, Fig. 4. Fig. 30 6 is a horizontal section taken on the line $y y$, Fig. 5.

Similar reference characters indicating corresponding parts in the views, let the numeral 5 designate what is ordinarily termed a "belt-machine," comprising a table 5^a , end drums 5^c , and an endless belt 5^d , operated by a worm 6, engaging a gear-wheel 7. The worm-shaft is journaled in a suitable stationary frame 8 and is provided with a cone-pulley 9, connected 35 with a pulley 10 on the motor-shaft 12 by means of a belt 13. The mechanism for giving the belt and table a laterally-reciprocating movement will now be described, special reference being made to Figs. 4, 5, and 6.

40 Upon a stationary frame 14 is mounted a draw-bar 15, comprising two axial stems 15^a and 15^c , and a yoke 15^d , connecting the said stems. Mounted on the yoke 15^d is a shaft or bearing 16, while a shaft 17 is mounted on 45 the stationary bed 14. Between these shafts

is located a vertically-movable horizontal shaft 18, carried by the toggle arms or members 19 and 20. There are two arms 19 interposed between the shafts 16 and 18 and two arms 20 located between the shafts 17 and 18. 55

Mounted on upright arms 14^a of the bed 14 is a crank-shaft 21. The crank 21^a of this shaft is connected with the shaft 18 by a pitman 22. The crank-shaft is rotated by connecting a pulley 23 thereon with any suitable 60 motor. As the crank-shaft is rotated the shaft 18 is raised and lowered and the reciprocating movement imparted to the draw-bar 15 and the concentrating apparatus 5, with which the draw-bar is connected. A spring 24 is interposed between a collar 25, mounted on the bed 14, and another similar collar, 26, fast on the draw-bar. The length of the draw-bar's stroke is regulated by adjusting the vertically-movable block 14^2 , in which the shaft 17 is 65 made fast. This block is located between the two toggle members 20 and is adapted to slide freely vertically on a post 14^e , formed integral with the bed 14. The upper extremity of the block 14^2 is provided with a horizontal lug 14^d , 70 apertured to receive a bolt 27, screwed into the top of the post 14^e . This bolt is threaded to receive two nuts, which engage the lug 14^d on opposite sides. The vertical position of the block, and consequently that of the shaft 17, 75 is regulated by the adjustment of these nuts.

The table 5^a is transversely inclined, and a trough 28 is arranged along its upper edge, just above the belt 5^d . This trough is separated by a partition 28^a into two compartments 28^c and 28^d . The compartment 28^c is farther to the right. (See Fig. 2.) Into this last-named compartment is fed the material to be treated in the form of pulp. The pure water is discharged into the compartment 28^d . 85 The pulp and water pass to the moving belt through apertures formed in the trough. Hence the pulp is distributed upon the upper right-hand corner of the belt, (see Fig. 2,) which is moving in the direction indicated by 90 the arrow. The reciprocation of the belt and table by the mechanism shown in Figs. 4, 5, and 6 is in a direction at right angles to the movement of the belt.

95 The special object of this invention is the 100

saving of the finer mineral particles or slimes which have escaped with the tailings from other machines.

The mechanism is so arranged that when 5 the shaft 18 of the toggle-joint moves upwardly the table is drawn backwardly or toward the left, referring to Fig. 3, while when the shaft 18 of the toggle moves downwardly the table is moved in the opposite direction, 10 or toward the right. Hence when the table is moving toward the left the tendency of the toggle-joint is to first impart a sudden impulse backward and then cause it to decrease gradually in speed until the limit of the stroke 15 is reached, while when it is moving in the opposite direction, or toward the right, the tendency of the toggle is to cause it to start slowly and gradually increase in speed until it reaches the limit of its stroke. The normal 20 result of the toggle movement is only approximately true in this case by reason of the action of the operating-crank, and the stop of the table is therefore only approximately sudden when it reaches its limit of movement toward the right. For all practical 25 purposes, however, the stop may be called a "sudden" stop and will be so termed in this specification, since substantially the same result would be accomplished by bumping the table against a stationary object when the table is traveling in the direction toward which it is desired to discharge the gangue and in a direction different from that in which the belt is traveling. This sudden stop carries 30 the gangue over the lower edge of the belt, while the finer mineral particles or slimes are carried over the end of the table by the moving belt. I have found by experiment that the gangue, whose particles are coarser 35 than the fine mineral particles or slimes, (the saving of which this invention is designed to effect,) is acted upon by the sudden stopping of the table to a much greater extent than the mineral particles which naturally assume a position underneath the gangue by virtue of their greater specific gravity. In other words, the gangue is carried downwardly over the lower edge of the belt by the sudden stopping of the table during each reciprocation, 40 while the fine mineral particles lying close to the belt are practically undisturbed thereby and are carried along with the belt and discharged at the end of the table.

It will be observed that the ordinary bumping-tables are so arranged that the table is bumped or suddenly stopped when moving in the direction toward which the mineral is traveling and are employed for the purpose of giving the mineral an impetus which shall 55 separate it from the gangue, while in my construction the table is stopped suddenly when moving in a direction different from that in which the mineral is traveling and for the purpose of imparting a separating impetus to the gangue.

In the ordinary belt-machine the lateral movement is an even or steady reciprocation for the purpose of agitating the material and allowing the mineral particles to settle, the gangue being separated therefrom by the action or force of the water alone. In the effort to do this effectually the transverse inclination of the belt is made considerable and much of the slimes or finer mineral particles are oftentimes carried away with the water 70 by reason of said inclination. By employing an operating mechanism adapted or whose tendency is to impart a separating impetus to the gangue to aid or supplement the separating action of the water I am enabled to 75 use a belt whose inclination varies only slightly from a horizontal plane. This feature is conducive to the holding of the slimes on the belt until they are carried over the end of the table and discharged, as heretofore explained. 80

To the belt frame or table is bolted a coupling-plate 30, adapted to connect the draw-bar extremity with the table. This extremity of the draw-bar is shouldered, as shown at 15^g, to engage the plate, being located between the 90 plate and the table. The coupling-plate is provided with a vertical open slot 30^a, extending downwardly from the reduced neck 15^h, upon which the coupling-plate is adapted to slide freely to permit the adjustment of the table 95 for the purpose of regulating its transverse inclination. The washer 26 bears against the coupling-plate and holds the parts in operative relation.

Having thus described my invention, what 100 I claim is—

1. The combination with an open-centered spring-actuated yoke having guide projections adapted to slide in bearings, of a drive-shaft, and toggle mechanism located within 105 the yoke and connected with the drive-shaft for actuating the yoke.

2. The combination with a draw-bar constructed and adapted to slide in suitable bearings, said draw-bar comprising a pair of axial 110 stems, and an open-centered yoke connecting said stems, and a spiral spring mounted on one of said stems, of a drive-shaft, and toggle mechanism located within the yoke and connected with the drive-shaft for actuating the 115 draw-bar.

3. The combination with a draw-bar constructed and adapted to slide in suitable bearings, said draw-bar comprising a pair of axial stems and a yoke connecting said stems, and a spiral spring mounted on one of said stems, of a drive-shaft, toggle-arms connected with a stationary support and with said draw-bar, a shaft interposed between and carried by said toggle-arms, said arms and shaft located within the yoke of the draw-bar, and a pitman operated by the drive-shaft and connecting the other shaft thereto. 120

4. The combination with a draw-bar constructed and adapted to slide in suitable bear- 125 130

ings, said draw-bar comprising end stems and intermediate yoke, and a spiral spring on one of the stems, of a drive-shaft, toggle-arms, and interposed shaft located within the open center of the yoke, a pitman driven by the drive-shaft and connected to the shaft between the toggle-arms, a stationary post, and a vertically-movable block adjustable with respect to said post and carrying one end of the toggle.

5 5. The combination with a draw-bar constructed and adapted to slide in suitable bearings, said draw-bar comprising end stems, and intermediate yoke, and a spiral spring on one of the stems, of a drive-shaft, toggle-arms, interposed shaft, a pitman driven by the drive-shaft and connected to the shaft between the toggle-arms, a stationary post, and a vertically-movable block adjustable with respect to said post and carrying one end of the toggle,

10 20 said toggle-arms, interposed shaft, post and block located within and encircled by the yoke

of the draw-bar whereby the parts are compactly arranged and in direct line with the application of the power.

6. The combination with a draw-bar constructed and adapted to slide in suitable bearings, said draw-bar comprising a pair of axial stems and an open-centered yoke connecting said stems, of a drive-shaft, toggle-arms connected with a stationary support and with said draw-bar, a shaft interposed between and carried by said toggle-arms, said arms and shaft located within the yoke of the draw-bar, and a pitman operated by the drive-shaft and extending to the other shaft.

30 35 In testimony whereof I affix my signature in presence of two witnesses.

ARTHUR R. WILFLEY.
